UNITED STATES PATENT OFFICE.

TOLBERT F. CHEEK, OF NEW YORK, N. Y., ASSIGNOR TO WELTE-MIGNON CORPORATION, OF NEW YORK, N. Y., A CORPORATION OF NEW YORK.

CABINET PLAYER.

Application filed September 20, 1923. Serial No. 663,829.

This invention has reference to that type of record-controlled piano playing mechanism (herein called "cabinet piano players") in which the player mechanism is mounted 5 within a casing which is formed separate from the piano and is movable to the piano, when the latter is to be played under control of a record, and away from the piano when the same is to be played by hand. In 10 this type of playing mechanism, there is a series of fingers or levers—hereinafter called "key operating levers"—one for each piano key—which in the operation of the mechanism protrude from the interior of the cabinet 15 and operate the keys of the piano, respectively, under control of a record; and the purpose of the present invention is to variously improve this type of playing mechanism with reference to these levers 20 and adjunctive elements. Among the improvements which this invention aims to effect are (1) the complete withdrawal of the key operating levers into the confines of the casing when they are not in use, without 25 requiring any deepening of the casing from front to rear to accommodate them in their withdrawn position; (2) a more expeditious movement of the several key operating levers from and into their position in which 30 they protrude from the casing for operation upon the piano keys; (3) adequate provision for the adjustment of the height of the key operating levers to that of the piano keys upon which they are to operate, without 35 necessitating any adjustment of the casing for this purpose; (4) ready adjustment of the key operating levers individually as necessary to bring about a uniform engagement of the same with the piano keys, 40 respectively.

These, and other purposes of the invention not necessary particularly to enumerate herein for the reason that they will be obvious to those familiar with this type of 45 piano playing mechanisms, are secured from the construction illustrated in the accompanying drawings and which exemplifies a preferred embodiment in which all of the stated purposes will be realized. It is to be 50 understood, however, that this is merely exemplary and that changes may be made without departing from the spirit of the invention as defined by appended claims.

In said drawings, wherein like characters of reference denote like parts in the several 55 views,

Fig. 1 is a side view, partly in section on the line 1—1 of Fig. 3, of the forward part of a grand piano, and a like view of a cabinet player in operative relation therewith, 60 with a part of an end wall of the casing broken away to disclose certain parts of the player mechanism therein,

Fig. 2 is a view of a cabinet player similar to Fig. 1, but with the key operating levers 65 withdrawn into the casing and the latter closed,

Fig. 3 is a rear elevation of a part of the cabinet open, with the key operating levers 70 in section,

Fig. 4 is a detail perspective view showing two of the key operating levers broken off at their outer ends and the adjacent part of the carrying and adjusting rail therefor,

Fig. 5 is a detail view, in perspective, of 75 one of the holding means for the upper ends of the guide rods upon which the ends of the carrying and adjusting rail are mounted.

A designates the case of a cabinet player. This case may be of any suitable construction, but as here shown it has a flat top a beneath which, in the upper portion of the case, provision is made for the tracker bar 10 and the feed and rewind rolls 11, 12, together with other parts not necessary herein to illustrate or describe, because well known, usually located adjacent said rolls for driving the same to thereby feed and rewind the note sheet. The rear wall of the case is provided with an opening a', through 90 which the outer ends of the several key operating levers protrude when in position to operate upon the piano keys. This opening also gives access to various parts of the player mechanism, as will be seen. A door 95 a'' is provided to close this opening when the key operating levers are in their withdrawn position.

From the tracker bar 10 several ducts, one of which (marked 13) is shown principally in dotted outline in Fig. 1, extends to the pneumatic mechanism for operating the player. The pneumatic mechanism preferably includes a striker pneumatic unit 14 which supports and controls the several 105 striker pneumatics 15 and 16 which are ar-

ranged in rows and in a staggered relation, the pneumatics 15 of one row respectively controlling the operations of the white keys of the piano while the pneumatics 16, of the 5 other row respectively, control the operation of the black keys of the piano. The illustrated pneumatics are of bellows form and the movable board of each has a striker rod of which those connected to the pneumatics 15 are marked 17 and those connected to the pneumatics 16 are marked 18. These rods are pivotally connected at their lower ends to the movable boards of the striker pneumatics, respectively, and all of them extend 10 through openings in a guiding member 19 suitably supported in proper position within the cabinet.

A series of key operating levers 20 pivotally mounted between their ends to have 20 movement about horizontal axes 20' are so arranged that in the operation of the mechanism they will be operated under control of the pneumatics 15 to operate the white keys of the piano, the inner ends of these levers 25 when in operative position being engaged by the upper ends of the arms 17, respectively, and their outer ends engaging said white keys, respectively; and a like series of key operating levers 21, pivotally mounted to 30 have movement, individually, about horizontal axes 21', and whose inner ends are engaged by the upper ends of the arms 18 and whose outer ends engage the black keys of the piano, when the key operating levers 35 are in operative position, are employed to operate the several black keys of the piano under control of the pneumatics 16.

These key operating levers are carried by a rail the preferred construction of which is 40 hereinafter set forth. As here shown they are pivotally attached to holding arms 22, 23 which depend from a member 24 which forms a part of the rail and serves as a carrier common to all the key operating 45 levers. The member 24 is preferably provided with a bead 22' which enters recesses in the respective arms 22 and with a second bead, 23', which is offset from the bead 22' and enters recesses in the several holding 50 arms 23. Fastening screws, one of which is indicated at 23'', are employed to supplement the beads and recesses in attaching the holding arms attached fixedly to the member 24, in a way which is effective and permits 55 quick and individual removal or replacement of the holding arms and key operating levers.

The carrier member 24 of the rail is mounted to have pivotal movement to carry the key operating levers bodily inward or outward with relation to the casing, the inward movement thereof being such as to 60 position the several key operating levers within the confines of the casing, as shown in Fig. 2, and the outward movement there-

of being such as to position the key operating levers in operative relation with the several strike pneumatics and with the piano keys. 65

In this particular embodiment of the invention the rail has end members 26 in 70 addition to the member 24 and these end members are undercut, to form projections 26' to be engaged by like projections 24' which extend from the ends of the members 24 and underlie the projections 26' when the member 24 is in its raised position with the key operating levers in position for operation upon the keys of a piano; and said member 24 is hingedly connected at its inner side, as indicated at 25 in Figs. 1 and 3, 75 to the inner side of the end members 26, the hinges being attached to and connecting the projections 24' and 26' together. Thus it will be seen that the movement of the member 24 is a swinging one relatively to the members 26 and to the casing and striker pneumatics and their striker rods and is downward and inward while withdrawing the key operating levers to their storage position entirely within the confines of the casing and upward and outward to their position for use. 80

It will be understood that the members 24 and 26 complementarily form the rail hereinbefore referred to and that this rail extends across the inside of the casing, substantially from one end wall to the other. Suitable means, as slotted keepers 28 attached to the pieces 26 and bolts 29, hinged to the projections 26' from the member 24 and adapted to enter the slots in said keepers and to be releasably secured to the keepers by wing nuts 30, for example, are provided to hold the member 24 releasably in its raised position with the key operating levers in operative relation with the strike pneumatics and in their position for use upon a piano. 90

It will be observed that the described construction of rail forms a simple and practical means by which the power of the strike pneumatics is transmitted directly to the rear ends of key operating levers by the striker rods 17 and 18, respectively, and which key operating levers are moved unitarily with the member 24 of the rail and bodily in the inward and upward and outward and downward directions hereinbefore referred to. In other words, it will be noted that the key operating levers are not formed of separate members pivotally connected to each other, so 110 that the outer members can be swung downward and inward or upward and outward relatively to the other members, and in which constructions the power is applied to the inner members, but on the contrary each key operating lever is formed of a single member. The advantages of the referred 115 120 125

to inward and downward and upward and outward movements, in the positioning of said levers entirely within the casing and in the positioning of the same for operation upon the piano keys, respectively, thus are obtained by a most simple and efficient means as compared with those constructions in which the key operating levers are divided.

Moreover, the described construction of rail and correlation of key operating levers therewith has further advantages in that it permits of unitary adjustment of the height of the rail and key operating levers and of unitary movement of said rail and key operating levers inward and outward by the simple, easily operated and effective means now to be described.

31 designates vertical rods which are arranged within the casing near the opposite walls thereof and extend through openings in the rail members 26. The rail is slidably mounted upon these rods and hence may be raised or lowered thereon to thereby adjust the height of the key operating levers to a proper level with relation to that of the piano keys. It is held in its adjusted position upon the rods by suitably fastening elements, indicated at 31. A further adjustment of the level of the key operating levers, is provided for through the medium of regulating screws 32 which are mounted in the inner ends of the respective key operating levers and are provided with buttons 32' to engage heads 32'' on the upper ends of the corresponding arms 17 or 18 of the striker pneumatics. These regulating screws are accessible through the openings *a* in the cabinet, but to render them, as well as the rail, more accessible for the purposes of adjustment, and also to facilitate the operation of mounting the rail with the several key operating levers thereon upon the rods 31 and their removal from the cabinet, said rods are pivotally mounted so that they may be swung outward from one end to either bring the rail and key operating lever closer to or entirely through the opening *a* of the cabinet. As here shown, the lower ends of the rods are provided with bearings 33 upon shafts 33' suitably supported by the end walls of the cabinet. Suitable provision for holding them in position within the cabinet and for releasing them for their swinging movement is made in this exemplification of the invention by means of collars or heads 34 having lateral wings 35, slidably mounted in guides 36 attached to the end walls of the cabinet in position to receive the upper ends of the rods respectively. By pressing these collars or heads upward within their guides the upper ends of the rods 31 are released and said rods will then be permitted to be moved, or to move, pivotally forward about their axes at 33. When

in this position, the rail with the strike levers may be easily placed therein or removed therefrom, and the regulating screws will be in very convenient position for removal, replacement or adjustment, as will be obvious. In returning the rail to operative position within the casing, it is only necessary to press the rods back until their upper ends register with the openings in the collars or heads 34 whereupon the latter will drop or may be dropped into holding position upon said rods.

It will be apparent that this invention provides means of simple and practical nature whereby the height of the several key operating levers may be adjusted in accord with the height of the piano keys upon which levers are to operate, and that this adjustment of all of the levers may be quickly effected at once merely by loosening the fastening elements 31' and then raising or lowering the rail formed of the members 24 and 26, and securing it in its selected position by tightening the wing fastening elements. It will also be apparent that the two ends of the rail are relatively adjustable, if necessary to bring the key operating levers into a substantially horizontal plane corresponding with that of the piano keys. Further, it will be noted that the key operating levers may be leveled individually to compensate for any imperfect alignment of the piano keys or of the levers, by individual adjustment of the regulating screws 32; and finally it will be noted that when the cabinet is not in operative relation with the piano the key operating levers may occupy a vertical position within the confines of the case and the door *a''* may be closed, thereby avoiding any unsightly projections from the casing and allowing the latter to stand flush with a wall of the room. When the key operating levers are in this position they may be raised into their operative position, as a unit, by the simple operation of raising the rail-member (carrier) 24 on its hinges at 25 and by fastening it to the end pieces 26 through the medium of the swinging bolts 29, keepers 28, and nuts 30. When the levers are in this, operative, position and it is desired that they again be arranged within the confines of the casing it is only necessary to slacken the nuts 30 sufficiently to free the bolts 29, whereupon the member 24 with the attached key operating levers will fall gravitationally to the position shown in Fig. 2.

It is considered to be unnecessary to describe or illustrate herein those parts of the player mechanism which produce the necessary air tensions within the mechanism, or which operate or control the operation of the record and striker pneumatics under control of said air tensions, for the reason that these parts form no essential part of the

present invention, as any suitable means, several of which are known in the art, may be employed for these purposes.

Having thus described the invention, what I believe to be new and desire to secure by Letters Patent, is:—

1. A cabinet piano player comprising a casing having an opening, striker pneumatics and their striker rods, a rail mounted within the casing and extending across the same and formed of complementary members one of which is mounted to swing relatively to the remainder of the rail in an inward and downward direction and in an outward and upward direction, and a series of key operating levers pivotally connected between their ends to the swinging member of the rail and movable bodily therewith and inwardly in a downward direction to position them within the confines of the casing and outwardly in an upward direction to position them with their ends protruding from the casing, the inner ends of the levers when in the latter position being in operative relation with the striker rods, and fastening means to hold the swinging member of the rail releasably in its raised position.
2. A cabinet piano player comprising a casing having an opening, a member positioned within the casing and extending across the same and mounted to swing in an inward and downward direction and in an outward and upward direction, and a series of key operating levers each pivoted between its ends to said member and movable bodily therewith relatively to the casing-opening, inwardly in a downward direction and upwardly in an outward direction between their stored and operative positions.
3. A cabinet player comprising a casing having an opening, a rail mounted within the casing and extending across the same, said rail having a member which is hinged-ly connected to it to swing in an inward and downward direction and in an outward and upward direction, a series of key operating levers pivotally connected between their ends to the swinging member of the rail and moved bodily therewith inwardly in a downward direction and upwardly in an outward direction between their stored and operative positions, and means to secure the swinging member releasably to the rail in one of its positions.

4. A cabinet player comprising a casing having an opening, a rail mounted within the casing and extending across the same, said rail having a plurality of members provided with projections which respectively underlie and overlie each other, and also having a hinging means to permit one member to be swung relatively to the remainder of the rail, means to secure the swingable member releasably to the rail in one position

of said member, and a series of key operating levers pivotally connected to said swingable member.

5. A cabinet player comprising a casing having an opening, a rail mounted within the casing and extending across the same, said rail having a plurality of members provided with projections which respectively underlie and overlie each other, and also having a means which pivotally connects one of its members to the rail to permit said member to be swung relatively to the rail and within the casing in an inward and downward direction and in an outward and upward direction, a series of key operating levers pivotally connected between their ends to the swinging member of the rail and movable bodily therewith, and means to secure the swinging member in one of its positions releasably to the rail.

6. A cabinet piano player comprising a casing having an opening, a rail mounted within the casing and formed of complementary members one of which is mounted to have swinging movement relatively to the remainder of the rail, releasable means to secure said swinging member to the rail in one position of the swinging member, and a series of key operating levers pivotally connected to said swinging member and movable bodily therewith between their stored and operative positions.

7. A cabinet piano player comprising a casing having an opening, a rail mounted within the casing and formed of complementary members one of which is mounted to have swinging movement relatively to the remainder of the rail, a series of key operating levers pivotally connected to said swinging member and movable unitarily with the same between their stored and operative positions, and pivoted means connected to the rail and supporting the same to permit the rail as a whole and the key operating levers to be moved unitarily relatively to the opening in the casing.

8. A cabinet piano player comprising a casing having an opening, a rail mounted within the casing and formed of complementary members one of which is mounted to have swinging movement relatively to the remainder of the rail, a series of key operating levers pivotally connected to said swinging member and movable unitarily with the same between their stored and operative positions, pivoted means connected to the rail and supporting the same to permit the rail as a whole and the key operating lever to be moved unitarily relatively to the opening in the casing, and means releasable from the pivoted means to hold the latter releasably against pivotal movement.

9. A cabinet piano player comprising a casing having an opening, a rail mounted within the casing and formed of comple-

mentary members one of which is mounted to have swinging movement relatively to the remainder of the rail, a series of key operating levers pivotally connected to said 5 swinging member and movable unitarily with the same between their stored and operative positions, and means upon which the rail as a whole is adjustable up and down to variably regulate the height of the key 10 operating levers to accord with that of the keys.

10. A cabinet piano player comprising a casing having an opening, a rail mounted within the casing and formed of complementary members one of which is mounted to have swinging movement relatively to the remainder of the rail, a series of key operating levers pivotally connected to said 15 swinging member and movable unitarily with the same between their stored and operative positions, and means upon which the rail as a whole is adjustable up and down to variably regulate the height of the key 20 operating levers to accord with that of the keys, said means being pivotally mounted to be operative to swing the rail and the key operating levers outward relatively to the 25 opening in the casing.

11. A cabinet piano player comprising a 30 casing having an opening, key operating levers, a rail mounted within the casing and having a swingable member to which the key operating levers are pivoted, a rail supporting means upon which the rail is 35 adjustably mounted, and means to secure the rail in adjusted position to the rail supporting means.

12. A cabinet piano player comprising a 40 casing having an opening, key operating levers, a rail mounted within the casing and having a swingable member to which the key operating levers are pivoted, substantially vertical rods upon which the rail is 45 adjustably mounted, and separate means to fix the respective ends of the rail in adjusted position to said rods.

13. A cabinet piano player comprising a 50 casing having an opening, key operating levers, a rail mounted within the casing and having a swingable member to which the key operating levers are pivoted, a pivotally mounted support for the rail, and releasable means to engage the support and hold it in one of its positions.

55 14. A cabinet piano player comprising a casing having an opening, key operating levers, a rail mounted within the casing and having a swingable member to which the key operating levers are pivoted, a pivotally mounted supporting rod connected to the rail, and means including an element engageable with the rod and slidably relatively thereto to hold the rod releasably against pivotal movement.

60 65 15. A cabinet piano player comprising a

casing having an opening, key operating levers, a rail mounted within the casing and having a swingable member to which the key operating levers are pivoted, pivotally mounted supporting rods upon which the 70 ends of the rail are adjustably mounted, respectively, means to secure the rail adjustably along the length of the rods, and means including elements engageable with the rods and releasable therefrom, to hold the rods 75 against pivotal movement.

16. A cabinet piano player, comprising a casing having an opening, striker pneumatics, a series of key operating levers to be operated by the striker pneumatics, respectively, a rail to which the key levers are connected, pivotally mounted means by which the rail is supported to be swingable relatively to the opening in the casing, and a head slidable relatively to the pivotally 80 mounted means to hold the same releasably 85 in position within the casing.

17. A cabinet piano player, comprising a casing having an opening, striker pneumatics, a series of key operating levers to be operated by the striker pneumatics, respectively, a rail to which the key operating levers are connected, supporting rods for opposite ends of the rail, each rod having a 90 pivotal mounting at one end, and releasable holding means for the other ends of the rods, respectively, each of said means comprising a fixed guide and an element having an opening to receive the adjacent end 95 of the corresponding rod and wings to engage the fixed guide.

18. A cabinet piano player, comprising a casing having an opening, striker pneumatics, a series of key operating levers to be operated by the striker pneumatics, a rail to which the key operating levers are connected, supporting means for the rail and upon which the rail is vertically adjustable, a pivotal mounting for the rail supporting 105 means, and releasable means operative to hold the rail-supporting means in position 110 to support the rail within the casing.

19. A cabinet piano player, comprising a casing having an opening, striker pneumatics, a series of key operating levers to be operated by the striker pneumatics, respectively, a rail having a pivotally mounted member to which the key operating levers are pivotally connected, means to secure the 115 pivotally mounted member against accidental pivotal movement relatively to the rail, a rail supporting and guiding means upon which the rail is adjustable relatively to the casing to different selected heights, a pivotal 120 mounting for the rail supporting and guiding means, and releasable means to hold the rail supporting and guiding means in position.

20. A cabinet piano player, comprising a 125

- casing having an opening, striker pneumatics, a series of key operating levers to be operated by the striker pneumatics, respectively, regulating connections between the key operating levers and striker pneumatics, respectively, a rail having a pivotally mounted member to which the key operating levers are pivotally connected, means to secure the pivotally mounted member against accidental pivotal movement relatively to the rail, a rail supporting and guiding means upon which the rail is adjustable relatively to the casing to different selected heights, a pivotal mounting for the rail supporting and guiding means, and releasable means to hold the rail supporting and guiding means in position.

21. In a cabinet piano player, the combination with a plurality of series of striker

pneumatics, and corresponding series of key operating levers to be operated by the striker pneumatics, respectively, of a carrying member for the key operating levers having a plurality of longitudinal beads in different horizontal planes, elements to the lower ends of which the key operating levers of one series are pivoted between their ends, said elements having in their upper portions recesses to receive one of said beads, and elements having recesses in their upper portion to receive the other bead and to which the lower ends of the key operating levers of the other series are pivoted between their ends.

In testimony whereof I affix my signature.

TOLBERT F. CHEEK.
